UNITED STATES PATENT OFFICE.

JACK F. DAHL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed February 9, 1923. Serial No. 617,920.

To all whom it may concern:

Be it known that I, JACK F. DAHL, a citizen of the United States, residing at East Orange, in the county of Essex, State of New Jersey, have invented certain new and useful Improvements in Telephone-Exchange Systems, of which the following is a full, clear, concise, and exact description:

10 This invention relates to a telephone exchange system, and more particularly to a system in which operators are employed for extending connections incoming to their positions from offices having switching equipment.

In systems of this character, it is found desirable that the manual operators be given the information required for them to extend or complete connections, without the necessity of communicating orally with the calling subscriber in the machine switching office or with other operators. To this end, each operator's position in the manual office is provided with call indicating mechanism, including a set of number indicating devices, and a second call is awaiting attention, or if she has no other waiting call and the operator's position from a distant machine switching office with a signal lamp, the illumination of which advises the operator that a call is awaiting her attention on the corresponding trunk. At her convenience, she associates the calling trunk with the common indicating mechanism at her position and thereupon the wanted designation is set up and displayed before the operator who proceeds to complete the connection.

40 In arrangements of this character to provide each trunk circuit incoming to an operator's position from a distant machine switching office with a signal lamp, the illumination of which advises the operator that a call is awaiting her attention on the corresponding trunk. At her convenience, she associates the calling trunk with the common indicating mechanism at her position and thereupon the wanted designation is set up and displayed before the operator who proceeds to complete the connection.

45 In such cases, the assignment lamp of each of the several operators in an office of before the two trunk circuits will be lighted, and this character, it may frequently occur during busy hours of the day that an excessive number of calls simultaneously appear on the trunks at any given operator's position, while at the two positions adjacent thereto only comparatively few calls are awaiting operator, the lamp of the assigned trunk

50 calls shall not be unduly delayed on this account, provision is made whereby the adjacent operator at either side of a home opera-

tor's position may assist the home operator by attending to some of the calls awaiting attention at her position. When either operator attends to a waiting call she operates a display key to associate the trunk circuit upon which the call is incoming, with her own indicator mechanism. Thus, each operator has two groups of display keys, one group comprising keys

individual to each of the trunk circuits normally incoming to her own position and the other group comprising keys individual to such trunks for the use of the operators on either side of her position. When any

display key is operated, the aforementioned signal lamp of the corresponding trunk circuit is distinctively lighted to indicate to the operator, who has assumed the responsibility for extending the required connection, that the designation of the required connection is about to be displayed on her indicator.

An efficient operator noting the distinctive lighting of an assignment lamp will take up the plug of the corresponding trunk circuit which is operated automatically under the control of registering mechanism in the machine switching office to inform the manual operator of the number and character of the required connection. It is customary in arrangements of this character to provide each trunk circuit of her position, upon which

55 a second call is awaiting attention, or if she has no other waiting call and the operator's position from a distant machine switching office with a signal lamp, the illumination of which advises the operator that a call is awaiting her attention on the corresponding trunk. At her convenience, she associates the calling trunk with the common indicating mechanism at her position and thereupon the wanted designation is set up and displayed before the operator who proceeds to complete the connection.

60 In such cases, the assignment lamp of each of the several operators in an office of before the two trunk circuits will be lighted, and this character, it may frequently occur during busy hours of the day that an excessive number of calls simultaneously appear on the trunks at any given operator's position, while at the two positions adjacent thereto only comparatively few calls are awaiting operator, the lamp of the assigned trunk

65 calls shall not be unduly delayed on this account, provision is made whereby the adjacent operator at either side of a home opera-

70 tor, the lamp of the assigned trunk attention. In order that the completion of circuit of her position is flashed at a slow rate, while if the assignment is made by an

75 operator, the lamp is flashed at a faster rate.

To economize in the equipment of the manual office, it is proposed to employ the busy back and peremptory interrupters of the ringing machine, the former for flashing the assignment lamps slowly and the latter for flashing them at a faster rate. Since the peremptory interrupter is connected to battery, it becomes necessary to interpose a relay between the interrupter and the flashing circuits of the assignment lamps in order to supply interrupted ground potential to these circuits. As the office must remain in service twenty-four hours of each day, this relay would be in constant operation unless some provision were made to relieve it. Further, since the busy back interrupter must perform its other usual functions in the office to which it is assigned, it is essential that no load be added to it which may at any instant be so great as to burn out its contacts as might happen if a lamp at each position of the office were connected to the interrupter at the same instant. Again, the interrupter must be protected against being rendered ineffective through the accidental grounding of one of the lamp circuits. If, then, the operator's positions of the office are divided into groups and provision is made for associating the interrupters with the lamps of only the groups of positions in which calls are being displayed, and further provision is made for overlapping the groups for enabling the lamps of adjacent positions to be operated when a trunk circuit is assigned by an adjacent operator, the foregoing difficulties will be largely obviated.

It is, therefore, an object of this invention to provide improved means for associating interrupter mechanism with groups of operators' positions.

This and other features of the invention will more clearly appear from a consideration of the accompanying drawings and appended claims. Fig. 1 shows diagrammatically in the upper portion thereof a subscriber's line terminating in a machine switching office and such switching mechanism of the office as is necessary to extend connections from such line to trunk circuits extending to other manual offices of the exchange area. In the right portion of this figure, a portion of a manual operator's call indicator is disclosed and in the lower portion thereof, the mechanism of three groups of operators' positions is disclosed for associating the interrupters shown at the left of the figure with such positions.

Fig. 2 shows a trunk circuit incoming from the machine switching office shown in Fig. 1 arranged to extend connections to subscribers' lines, one of which is shown at the right of this figure.

The apparatus shown in the upper portion of Fig. 1 for extending connections

from the subscriber's line A comprises a line switch 100, a district selector 150, an office selector 175 and a central office register sender 110. This apparatus has only been diagrammatically illustrated herein since it enters only incidentally into the disclosure of this invention. For a full disclosure of apparatus of this character and the manner in which it functions, reference may be had to the patent to F. A. Stearn and F. J. Scudder, 1,395,977, issued November 1, 1921.

The trunk circuit shown in Fig. 2 and that portion of the indicator mechanism of the operator's position associated with the trunk circuit and shown in the right portion of Fig. 1, are of substantially the same type, as fully disclosed in the Patent 1,464,084, issued August 7, 1923, to A. E. Lundell and E. H. Clark, and reference may be had to such patent for a complete disclosure of circuits of this character.

In the lower left corner of Fig. 1, two interrupters 107 and 108 are disclosed. These interrupters are both operated from the ringing machine of the manual office Y, interrupter 107 being the usual busy back interrupter and 108 the usual peremptory interrupter. The operators' positions of the office Y are divided into groups, each group comprising eight positions and each group having relay equipment associated therewith for controlling the connection of the interrupters 107 and 108 with the flashing circuits of the assignment lamps of all trunk circuits of the positions of the group. In Fig. 1, the relay equipment of three such groups of positions has been disclosed in the three rectangles indicated by the dot and dash lines, these groups being the first, an intermediate and the last groups. The indicator mechanism fragmentarily disclosed, is shown as belonging to operator's position No. 1 of the first group.

Briefly, should the operator at any one of the first seven positions of the first group assign her individual indicator to a trunk circuit, relay 111 will operate in turn operating relays 114 and 115 to associate the interrupters 107 and 108 with all of the flashing circuits of assignment lamps of the eight positions of the group. Should either the operator at the eighth position of the first group or the operator at the first position of the second group, which, for convenience, may be assumed to be the intermediate group illustrated, assigns her indicator to a trunk circuit, relay 116 will operate in turn operating relays 114 and 115 of the first group and relays 117 and 118 of the second group to associate the interrupters with all of the flashing circuits of the assignment lamps of the first and second groups. Should the operator at any of the positions 2 to 7, inclusive, of the second group assign her indicator to a trunk cir-

cuit, relay 119 will operate in turn, operating relays 117 and 118 for associating the interrupters with the flashing circuits of the assignment lamps associated with the operators' positions of the second group. Similarly, the connection of the interrupters is controlled by the remaining intermediate and last groups of operators' positions.

Having now briefly described the apparatus and the manner in which it functions, it is thought that the invention will be more clearly understood from a detailed description thereof. It will, therefore, be assumed that the subscriber A whose line terminates in the machine switching office X desires a connection with a subscriber B whose line terminates in the manual office Y. The calling subscriber A, to initiate the call, removes his receiver from its switchhook and through the operation of the line switch 100 obtains a connection over the brushes of this switch and the lower contacts of cams 101 and 102 of the sequence switch of the district selector 150, with the central office sender 110. As soon as the central office sender is connected with the calling line, the usual dial tone is transmitted and the calling subscriber thereupon proceeds to dial the several digits of the designation of the desired line B. The registers of the office sender record the several digits dialed by the subscriber and, in the well known manner, the sender then proceeds to control the setting of the district selector 150 and the office selector 175 in accordance with the office designation of the desired line. In the present case, it is assumed that the brushes of the office selector 175 are positioned upon the terminals of a trunk circuit 105—106 incoming to the office Y.

Upon the seizure of the trunk circuit 105—106, a circuit becomes established for the trunk relay 200 which may be traced in part from ground, through the left winding of relay 200, the left normal contact of relay 201, the lower left winding of repeating coil 202, conductor 203, the innermost lower armatures and back contacts of relays 204 and 205, conductor 106, lower brushes of switches 175 and 150, lower contact of cam 104, through the controlling circuit of the office sender, returning over the lower contact of cam 103, the upper brushes of switches 150 and 175, conductor 105, innermost upper armatures and back contacts of relays 205 and 204, conductor 208, upper left winding of repeating coil 202, right normal contact of relay 201 to battery through the right winding of relay 200. At the office sender, upon the closure of this circuit, the sender is prepared for transmitting code impulses for transferring the numerical designation of the desired line to the manual office where it is to be recorded upon a call indicator.

At the trunk circuit, relay 200 upon energizing closes a circuit for relay 209 which may be traced from battery, at the outer right armature and back contact of relay 210, winding of relay 209, the right armature and back contact of relay 212 to ground at the armature and contact of relay 200. Relay 209, upon energizing, closes a locking circuit for itself extending from battery through its outer right armature and contact, its winding, and to ground at the armature and contact of relay 200 and, at its inner right armature and front contact, establishes a circuit for the assignment lamp 213. This circuit may be traced from battery, through lamp 213, the left non-inductive winding of relay 214, the inner right armature and front contact of relay 209 to ground. The home operator, it being assumed that she is free at this time to attend to this call, noting the illumination of lamp 213, depresses the home display key 211, associated with the trunk circuit corresponding to the lighted lamp 213, whereupon a circuit is established for the assignment relay 215. This circuit may be traced from battery through the winding of relay 123 of the indicator control circuit shown in Fig. 1, conductor 216, the lower armature and back contact of relay 217, conductor 218, the right winding of relay 215, the outer left armature and front contact of relay 209, the lower contact of key 211, conductor 243, the armature and back contact of relay 125 to ground at the right armature and back contact of relay 126. Relays 123 and 215 energize in this circuit.

Relay 215, upon energizing, closes a locking circuit for itself extending from battery on conductor 218 through both of its windings to ground at the front contact of its inner left armature and also closes an obvious circuit for relay 210. Relay 210, upon energizing, opens at the back contact of its outer right armature the initial energizing circuit of relay 209, and closes a circuit for relay 214 which may be traced from ground through the right winding of relay 214, the inner right armature and front contact of relay 210 to battery at the outer right armature and contact of relay 209. Relay 210 also prepares a flashing circuit for the lamp 213 which later becomes effective following the deenergization of relay 209. With relays 214 and 215 now energized, a circuit is closed for relay 205 which may be traced from battery, through the left armature and contact of relay 214, conductor 219, winding of relay 205, conductor 220, outer left armature and contact of relay 215, conductor 231, winding of relay 125 to ground at the left armature and back contact of relay 126. Relays 205 and 125 energize in this circuit, relay 205 disconnecting the windings of trunk relay 200 from the trunk conductors.

105 and 106, and extending these conductors over conductors 206 and 207, through the windings of control relays 120, 121 and 122 of the call indicator of the operator's position in which the trunk circuit 105—106 terminates.

Upon the disconnection of the windings of relay 200, following the energization of relay 205, the locking circuit of relay 209 is opened and relay 209 deenergizes opening the previously traced circuit of lamp 213. Relay 214 upon energizing closed a locking circuit for itself extending from ground through its right winding, its inner right armature and front contact to battery through the winding of relay 212, but relay 212 did not energize in this locking circuit as long as relay 209 remained energized since it was shunted by direct connection to battery through the outer right armature and contact of relay 209. With relay 209 now deenergized, however, relay 212 energizes in the holding circuit of relay 214 and at its right armature and back contact opens the initial energizing circuit of relay 209.

At the call indicator shown fragmentarily in Fig. 1, upon the energization of relay 123 thereof, holding ground was connected to conductor 124 through the outer left armature and back contact of relay 127 and through the left armature and front contact of relay 123 for holding the various switching and registering relays (not shown) of the indicator in their operated positions as soon as they are energized by the control relays 120, 121 and 122 in response to code impulses transmitted from the office sender 110. Ground on conductor 124 is also furnished to the armatures of the control relays for controlling the various operating functions of the call indicator. At its right armature and front contact, relay 123 connects ground to conductor 109, thence through the winding of relay 111 to battery. It will be noted that relay 111 is common to the first seven call indicators of the first seven operators' positions comprising the first group of positions. With relay 111 energized, a circuit is established for intermittently operating relay 114 which may be traced from battery through the winding of relay 114, upper armature and contact of relay 111, conductor 128 to ground through the busy back interrupter 107. A circuit is also established for intermittently operating relay 115 which may be traced from ground through the winding of relay 115, the lower armature and contact of relay 111, conductor 129, to battery through the peremptory interrupter 108.

With relays 114 and 115 both operating intermittently at different rates under the control of the interrupters 107 and 108, ground potential is supplied intermittently to all of the flashing leads corresponding to

the leads 112 and 113 extending to all trunk circuits terminating in the first eight operators' positions comprising the first group of positions. Since it has been assumed that the home operator has attended to the call incoming on trunk circuit 105—106, relay 221 is at this time unoperated and, therefore, with relay 209 deenergized a circuit is established for flashing the assignment lamp 213 of this trunk circuit at a slow rate to indicate to the home operator that a line designation is being registered upon her indicator and that the call so being registered will later require her attention. The circuit for lamp 213 may now be traced from battery through the lamp 213, the left non-inductive winding of relay 214, the inner right armature and back contact of relay 209, the left armature and front contact of relay 210, lower armature and back contact of relay 221, conductor 113, the upper armature and contact of relay 114 to ground. The intermittent operation of relay 115 is at this time ineffective, unless an operator at some other position of the group has assigned a trunk to her indicator on a team work basis.

In response to code impulses transmitted from the office sender 110 in accordance with the numerical designation recorded upon the registers thereof, the indicator at the operator's position functions to register the several digits of the line designation, following which the line designation becomes displayed upon the indicator.

During the transmission of the code impulses and following the setting of the stations relays of the indicator, ground potential is connected to the ringing selection conductors 244 and 245, it being assumed that the party W on the called line is desired. Upon the connection of ground potential to conductor 244, a circuit is established over this conductor, upper armature and contact of relay 205, conductor 237 to battery through the winding of relay 233. This relay, upon operating, locks through its winding and its lowermost armature and contact to ground at the inner left armature and front contact of relay 212. Ground potential connected to conductor 245 causes the operation of relay 232 over a circuit which may be traced in part from conductor 245, lower armature and front contact of relay 205, conductor 238 to battery through the winding of relay 232. Relay 232 upon energizing locks through its lower armature and contact to ground at the inner left armature and contact of relay 212.

When the code impulses have all been received from the office sender 110, relay 126 becomes energized. These operations have not been described in detail herein since they form no essential part of this invention and since they are fully described in the patent

of A. E. Lundell and E. H. Clark hereinbefore referred to. Relay 126 upon energizing opens the previously traced circuit extending through the windings of relays 125 and 5 205, thereby causing the release of these relays. Relay 205, upon deenergizing, disconnects conductors 206 and 207 from the trunk conductors 105 and 106, and reconnects the trunk conductors with the windings of trunk 10 relay 200. Relay 200 now becomes energized over the previously traced circuit extending to the office sender, whereupon the office sender, having performed all of the 15 functions required of it, is dissociated from the connection. The talking circuit is now established from the calling line over the upper contacts of cams 101 to 104, inclusive, and the brushes of switches 150 and 175 to the trunk conductors 105 and 106, and relay 20 200 is held energized thereover. A new holding circuit is now established for relay 212, which may be traced from battery through the right armature and front contact of relay 212 to ground at the armature 25 and contact of relay 200 in shunt of the winding of relay 214. Relay 214 thereupon deenergizes opening at its left armature and contact the initial energizing circuit of relay 205.

30 The operator, noting the illumination of the lamps of the indicator, takes up the plug 223 of the trunk circuit designated by the flashing lamp 213 and tests the sleeve of jack 227 to determine if the desired line is 35 idle, and upon finding it idle, inserts the plug in the jack. Upon the insertion of the plug in the jack, sleeve relay 217 is energized in a circuit which may be traced from battery through the winding of ringing relay 40 228, right armature and back contact of relay 229, armature and back contact of relay 230, outer left armature and contact of relay 212, outer right armature and back contact of relay 214, winding of relay 217, sleeve of plug 223, sleeve of jack 227 to ground 45 through the cut-off relay 246 of the called line. Lamp 224 being shunted by the winding of relay 228 does not energize at this time. Relays 246 and 217 energize in this 50 circuit, relay 217 disconnecting the tip of plug 223 from conductor 226 which extends through the upper armature of relay 221 to the test winding of the operator's head set, and connecting the tip of the plug to the upper armature of the ringing relay 228. Relay 217 at its lower armature and back contact opens the holding circuit previously 55 traced through the windings of relays 215 and 123, whereupon these relays deenergize, relay 123 disconnecting ground potential from the holding conductor 124 thus releasing all energized relays of the call indicator and extinguishing the lighted lamps. Relay 60 123 also removes ground potential from conductor 109 releasing relays 111, 114 and 115,

if at this time, no other operator's position has an indicator assigned to trunk circuits incoming to such position. Relay 215, upon deenergizing, opens the circuit of relay 210, whereupon the circuit over which lamp 213 was flashed is opened and the lamp is extinguished.

Ringing relay 228 upon energizing closes a circuit for connecting the source 239 of ringing current to the called line. With relays 217 and 233 energized, a circuit is established for relay 241 which may be traced over the pick-up conductor 240, normal right contacts of relay 241, the winding of relay 241, the upper armature and contact of relay 233, the innermost lower armature and front contact of relay 217 to ground at the armature and contact of relay 212. Relay 241 upon energizing locks through the alternate contact of its right armature over the

circuit previously traced to ground at the inner left armature of relay 212. With relays 228, 232, 233 and 241 energized the circuit, over which current from the source 239 is applied to the called line, may be traced from the source 239, the right winding of marginal relay 230, the upper armature and front contact of relay 232, the left armature and contact of relay 241, the innermost

lower armature and contact of relay 233, the upper armature and front contact of ringing relay 228, the upper armature and front contact of relay 217, tip of plug 223, tip of jack 227, the bell 242 at the substation of the desired line, ring of jack 227, ring of plug 223, lower armature and front contact of relay 228 to ground at the innermost upper armature and front contact of relay 233.

In response to the ringing of bell 242, the called subscriber removes his receiver from its switchhook, whereupon marginal relay 230 becomes energized and at its armature and contact opens the shunt around the winding of relay 229. Relay 229 now energizes in series with relay 228 and at

its right armature and front contact closes a locking circuit for itself and for relays 246 and 217 in shunt of the winding of ringing relay 228. This circuit may be traced from battery through the right armature and front contact of relay 229, the winding of relay 229, the outer left armature and contact of relay 212, the outer right armature and back contact of relay 214, the winding of relay 217, sleeve contacts of plug 223 and jack 227 to ground through the winding of relay 246. Relay 228 being shunted now deenergizes disconnecting the

source of ringing current 239 from the conductors of the called line and connecting the conductors of the called line to the right windings of repeating coil 202 through the winding of supervisory relay 236. A circuit is now established for the supervisory

relay 236 which may be traced from the

105 110 115 120 125 130

non-grounded pole of battery, the lower right winding of repeating coil 202, winding of relay 236, the lower armature and back contact of relay 228, ring of plug 223, 5 ring of jack 227, through the substation of subscriber B, tip of jack 227, tip of plug 223, upper armature and front contact of sleeve relay 217, upper armature and back contact of relay 228 to ground through the 10 upper right winding of repeating coil 202. Relay 236, upon energizing, closes a circuit for reversing relay 201 which may be traced from battery, through the winding of relay 201, armature and contact of relay 236 to 15 ground at the left armature and contact of relay 229. Relay 201, upon energizing, reverses the connection between the windings of trunk relay 200 and conductors 105 and 106 of the trunk circuit for supervisory purposes.

Upon the termination of the conversation, the subscribers A and B will restore their receivers to their respective switchhooks whereupon the apparatus at the machine 25 switching office X restores in the well known manner and the previously traced circuits of relays 200 and 236 will be opened. Relay 200, upon deenergizing, opens the holding circuit of relay 212, which, in turn, opens 30 the locking circuits of relays 232, 233 and 241 and opens the previously traced holding circuit extending through the windings of relays 229, 217 and 246. A circuit is now effective for the disconnect lamp 224 which 35 may be traced from battery through lamp 224, the winding of relay 217, sleeve contacts of plug 223 and jack 227 to ground through the winding of cutoff relay 246. The operator, noting the illumination of the 40 disconnect lamp 224, removes the plug 223 from jack 227, whereupon relays 217 and 246 release. All apparatus of the trunk circuit employed in establishing the connection is now in normal condition.

45 Had the home operator been busy at the time the call came in upon the trunk circuit 105—106 of her position and the adjacent operator been free, the adjacent operator would have reached over and depressed the 50 team work display key 225 corresponding to the trunk circuit the assignment lamp 213 of which was lighted. Upon the depression of key 225, a circuit becomes established for the team work assignment relay 222 55 which may be traced in part from ground applied to conductor 247 at the indicator of the adjacent operator's position, through the upper contact of key 225, the inner left armature and front contact of relay 209, 60 right winding of relay 222, innermost upper armature and back contact of sleeve relay 217, conductor 248 to battery through a relay of the adjacent operator's indicator corresponding to relay 123. Relay 222 65 upon energizing closes the circuit of relay

210 and at its outer left armature and contact closes a circuit for relays 204 and 221 and a relay of the adjacent operator's indicator corresponding to relay 125 over a circuit which may be traced from ground 70 at the adjacent operator's indicator through the relay corresponding to relay 125, conductor 249, the outer left armature and front contact of relay 222, the upper winding of relay 221, winding of relay 204, left armature and contact of relay 214 to battery as soon as relay 214 becomes energized following the energization of relay 210.

75 Relay 221 upon energizing locks from battery through its lower winding and intermediate armature and contact to ground at the inner left armature and front contact of relay 212. Relay 212 becomes energized in the holding circuit of relay 214 following the energization of relay 210 and the deenergization of relay 209, in the manner previously described. With relay 204 energized, the conductors of trunk circuit 105—106 become connected through the innermost armatures and front contacts of relay 204 to conductors of the group 234 leading to the indicator mechanism of the adjacent operator's position. Upon the energization of relay 204, relay 200 becomes deenergized. The assignment lamp 213 is 80 now disconnected from ground at the inner right armature and front contact of relay 209.

85 When the adjacent operator's indicator was assigned to the trunk circuit 105—106, it being assumed that the adjacent operator is at position 2 of the first group, ground potential was connected to the conductor 109 causing the operation of relays 111, 114 and 115, as previously described. When, therefore, relay 209 deenergizes, a circuit is established for repeatedly flashing the lamp 213 which may be traced from battery through the lamp 213, the non-inductive winding of relay 214, the inner right armature and back contact of relay 209, the left armature and front contact of relay 210, the lowermost armature and front contact of relay 221, conductor 112, the upper armature and front contact of relay 115 to ground. It will be recalled that relay 115 is operated intermittently following the energization of relay 111 under the control of the peremptory interrupter 108. The lamp 213 continues to flash at a fast rate until the adjacent operator, seeing the display of the required line designation upon her indicator, proceeds to extend the connection by reaching over to the home operator's position, taking up the plug of the trunk circuit 105—106 and inserting it into the multiple of the desired line. Since the lamp 213 is flashing at a fast rate, both the home and adjacent operators recognize that the call is one which the adjacent operator has as 90 95 100 105 110 115 120 125 130

signed and that the adjacent operator should attend to its extension. From this point, the call proceeds in exactly the same manner as though the home operator had attended to it.

Had the call come in upon a trunk circuit at position No. 8 of the first group, and the operator at such position been too busy to attend to it at the time, and the adjacent op-

- 10 erator at position 1 of the next group of positions had attended to the call, then relay 116 would have become operated by ground connected to the conductor 180 extending to the armature contact of the relay corresponding to relay 123 of such adjacent operator's indicator. With relay 116 energized, relays 114 and 115, associated with the first group of operators' positions and relays 117 and 118 associated with the next intermediate group of positions become intermittently operated under the control of the interrupters 107 and 108. The circuit for relay 114 may be traced from battery through the winding of this relay, the innermost lower armature and contact of relay 116, conductor 128 to ground through interrupter 107. The circuit for relay 115 may be traced from ground through the winding of this relay, uppermost armature and contact of relay 116, conductor 129 to battery through interrupter 108. The circuit for relay 117 may be traced from battery through the winding of relay 117, conductor 131, the lowermost armature and contact of relay 116, conductor 128 to ground through interrupter 107. The circuit for relay 118 may be traced from ground through the winding of this relay, conductor 132, the innermost upper armature and contact of relay 116, conductor 129 to battery through interrupter 108. Through the intermittent operation of relays 114 and 115, ground potential is intermittently applied to conductors 134 and 133, respectively, corresponding to conductors 112 and 113, for flashing the lamps of the trunk circuits of the 8th position in the first group. Similarly, relays 117 and 118 furnish interrupted ground potential to conductors 135 and 136 corresponding to conductors 112 and 113, for flashing the assignment lamps of all trunk circuits of the first position of the intermediate group. It will, of course, be understood that only one lamp of each position will actually be flashed, since it is possible for the operator at a position to assign but one trunk at a time to her indicator mechanism.

The control of the application of intermittent current to the lamp circuits of positions in succeeding groups is exercised in substantially the manner hereinbefore described and further detailed description thereof is therefore not necessary. From the foregoing it will be apparent that the accidental grounding of any lamp circuit

will only affect the operation of a portion of the positions in the group in which the trouble occurs, the remaining or major portion of the office being still effective. Further it will be apparent that through the grouping of the operators' positions, the possible load upon either of the interrupters at a given instant is materially reduced.

What is claimed is:

1. In a telephone exchange system, a plurality of operators' positions divided into groups, trunk circuits incoming to said positions, a signal individual to each of said trunk circuits, a signal operating means common to all of said trunk circuits, relay means common to each group of operators' positions for associating said operating means with the signal of any of the trunk circuits incoming to the positions of the respective groups, and means operative upon the response of any operator at a group of positions for energizing the relay means common to said group. 75

2. In a telephone exchange system, a plurality of operators' positions divided into groups, an indicator at each of said positions, trunk circuits incoming to said positions, a signal individual to each of said trunk circuits, a signal operating means common to all of said trunk circuits, relay means common to each group of operators' positions for associating said operating means with the signal of any of the trunk circuits incoming to the positions of the respective groups, and means operative when any indicator of the group of positions is assigned to an incoming trunk for operating the relay means common to said group. 90

3. In a telephone exchange system, a plurality of operators' positions divided into groups, trunk circuits incoming to said positions, a lamp signal individual to each of said trunk circuits, an interrupter common to all of said trunk circuits, relay means common to the operators' positions of each group for associating said interrupter with the signal of any of the trunk circuits incoming to the positions of the respective groups to flash said signal, and means operative upon the response of any operator at a group of positions for energizing the relay means common to the operators' positions of said group. 105

4. In a telephone exchange system, a plurality of operators' positions divided into groups, trunk circuits incoming to said positions, a lamp signal individual to each of said trunk circuits, an interrupter common to all of said trunk circuits, and means common to adjacent operators' positions of adjoining groups for associating said interrupter with the signal of any of the trunk circuits incoming to the positions of said adjoining groups. 120

5. In a telephone exchange system, a plurality of operators' positions divided into groups, trunk circuits incoming to said positions, a lamp signal individual to each of 5 said trunk circuits, an interrupter common to all of said trunk circuits, means common to the operators' positions of each group for associating said interrupter with the signal of any of the trunk circuits incoming to the 10 positions of the respective group, and means common to adjacent operators' positions of adjoining groups for associating said interrupter with the signal of any of the trunk circuits incoming to the positions of said 15 adjoining groups. 70
6. In a telephone exchange system, a plurality of operators' positions divided into groups, trunk circuits incoming to said positions, a signal individual to each of said 20 trunk circuits, an interrupter common to all of said trunk circuits, a relay common to the operators' positions of each group for associating said interrupter with the signal of any of the trunk circuits incoming to the 25 positions of the respective group, and means operative upon the response of any operator at a group of positions for energizing the relay means common to the operators' positions of said group. 80
7. In a telephone exchange system, a plurality of operators' positions divided into groups, trunk circuits incoming to said positions, a signal individual to each of said 30 trunk circuits, an interrupter common to all of said trunk circuits, a relay common to the operators' positions of each group for associating said interrupter with the signal of any of the trunk circuits incoming to the 35 positions of the respective group, and a 90 second relay common to adjacent positions of adjoining groups for associating said interrupter with the signal of any of the trunk circuits incoming to the positions of said adjoining groups. 95
8. In a telephone exchange system, a plurality of operators' positions divided into groups, trunk circuits incoming to said positions, a signal individual to each of said 40 trunk circuits, an interrupter common to all of said trunk circuits, a relay for applying 100 operating potential to the circuits of all signals of the positions of a group, and a second relay under the control of any operator of the group of positions for connecting said first relay with said interrupter whereby said first relay is intermittently operated. 110
9. In a telephone exchange system, a plurality of operators' positions divided into 60 groups, trunk circuits incoming to said positions, a lamp signal individual to each of said trunk circuits, an interrupter common to all of said trunk circuits, a relay for applying operating potential to the circuits of all signals of the positions of a group, a 115 second relay under the control of any operator of the group of positions for connecting said first relay with said interrupter whereby said first relay is intermittently operated to flash said signal. 75
10. In a telephone exchange system, a plurality of operators' positions divided into groups, trunk circuits incoming to said positions, apparatus at each of said positions, means operable to extend a trunk circuit to the apparatus of either of two adjacent positions, a signal for each of said trunk circuits, and means common to the positions of each group and responsive to said last named means for operating said signal distinctively to indicate to which apparatus 85 said trunk circuit is extended. 80
11. In a telephone exchange system, a plurality of operator's positions divided into groups, trunk circuits incoming to said positions, an indicator at each of said positions, a signal associated with each of said trunk circuits, a key for each trunk circuit for extending it to the indicator of the position to which the trunk is incoming, a second key for each trunk circuit for extending it to the indicator of an adjacent position, signal operating means common to all of said trunk circuits, and means common to the positions of each group and responsive to the operation of either of the keys of each 100 trunk circuit incoming to a group of positions to effect a distinctive operation of said signal for indicating to which of said indicators a trunk circuit is extended. 100
12. In a telephone exchange system, a plurality of operator's positions divided into groups, trunk circuits incoming to said positions, an indicator at each of said positions, a signal associated with each of said trunk circuits, a key for each trunk circuit for extending it to the indicator of the position to which the trunk is incoming, a second key for each trunk circuit for extending it to the indicator of an adjacent position, means common to all of said signals for intermittently operating them at different rates, means common to each group of positions and responsive to the operation of one of said first mentioned keys of the group for causing the intermittent operation of an associated signal at one rate and responsive to the operation of one of said second mentioned keys of the group for causing the intermittent operation of the associated signal at a different rate. 115
13. In a telephone exchange system, a plurality of operator's positions divided into groups, trunk circuits incoming to said positions, an indicator at each of said positions, a lamp signal individual to each trunk cir- 120 125 130

cuit, a key for each trunk circuit for extending it to the indicator of the position to which the trunk circuit is incoming, a second key for each trunk circuit for extending it to the indicator of an adjacent position, a low frequency interrupter and a high frequency interrupter both common to all lamp signals, means common to the operators' positions of each group and responsive to the operation of a first mentioned key of the respective group for associating said low frequency interrupter with the signal of the corresponding trunk circuit and responsive to the operation of a second mentioned key of the respective group for associating said high frequency interrupter with the signal of the corresponding trunk circuit, and means common to adjacent operator's positions of adjoining groups for associating said interrupters with the signals of the trunk circuits incoming to the positions of said adjoining groups.

14. In a telephone exchange system, a plu-

rality of operators' positions divided into groups, apparatus individual to each group but common to the positions of a group, means to render the apparatus of a group active under the control of any position in such group, and means to render simultaneously active the apparatus of adjacent groups under the control of a position adjacent an adjoining group.

15. In a telephone exchange system, a plurality of operators' positions divided into groups, apparatus individual to each group but common to the positions of a group, means to render the apparatus of a group active under the control of any position in such group, and means to render simultaneously active the apparatus of adjacent groups under the control of either adjacent position of adjoining groups.

In witness whereof, I hereunto subscribe my name this 6th day of February A. D., 1923.

JACK F. DAHL.
